The ornamental design for a rail for a suspended rail system, as shown and described.

DESCRIPTION

FIG. 1 is an isometric view of a rail for a suspended rail system, showing my new design;

FIG. 2 is an end view thereof;

FIG. 3 is a top view thereof;

FIG. 4 is a side view thereof; and,

FIG. 5 is a bottom view thereof.

The rail for a suspended rail system is shown with a symbolic break in its length. The appearance of any portion of the article between the break lines forms no part of the claimed design.

The broken lines shown illustrate environmental structure of the rail for a suspended rail system, and form no part of the claimed design.
